[57] CLAIM

The ornamental design for a vertically mounted holder,
as shown and described.

DESCRIPTION

FIG. 1 is a front right perspective view of a vertically
mounted holder showing my new design;
FIG. 2 is a front elevational view thereof;
FIG. 3 is a side elevational view taken from the right of
FIG. 2, the side opposite being a mirror image thereof;
FIG. 4 is a sectional view taken in the direction of the
arrows on line 4—4 of FIG. 2.

FIG. 1
